LOOM AND METHOD OF WEAVING.

Samuel Kaufman, Brooklyn, N. Y.

Application April 5, 1945, Serial No. 586,708

13 Claims. (Cl. 139—18)

1

This invention relates to looms and the method of weaving textile material, and more especially it relates to looms having novel and improved shed forming mechanism, and to improved procedure for the manufacture of woven material.

The chief objects of the invention are to provide in a novel manner for forming a shed of the warp threads to be woven; to provide simplification of apparatus; to obviate the use of heddles and heddle-operating mechanism commonly employed in weaving looms; to obviate the use of a batten and reed usually employed for beating in the filler or weft after it has been laid in the shed; to provide improved means for packing down the weft strand after it has been laid in the shed; to obviate the requirement of extraneous means for imparting tension to the warp filaments, and for imparting tension to the woven web; to provide a loom requiring less floor space than conventional looms employed for similar types of weaving; to provide an improved method of weaving; and to produce a superior woven product. Other objects will be manifest as the description proceeds.

Of the accompanying drawings:

Fig. 1 is a front elevation of a loom embodying the invention, parts being broken away;

Fig. 2 is a side elevation of the loom shown in Fig. 1, as viewed from the right thereof;

Fig. 3 is a perspective view of the weaving operation showing the shuttle laying a weft strand in the shed;

Fig. 4 is an elevation, on a larger scale, of one type of warp-handling arm employed in the apparatus, a part being broken away and in section;

Fig. 5 is a similar view of another type of warp-handling arm of the apparatus;

Fig. 6 is a section on the line 6—6 of Fig. 5;

Fig. 7 is a detail elevational view of two warp-handling arms at one extremity of their relative operative movements, and the work therein;

Fig. 8 is a view similar to Fig. 7 showing the relative positions of the warp-handling arms while at rest during the laying of the filler or weft strand; and

Fig. 9 is a view similar to Figs. 7 and 8 showing the warp-handling arms after they have passed each other and are beginning to tighten the warp threads about the weft strand.

Referring to Figs. 1 and 2 of the drawings, there is shown a loom structure comprising an open base structure designated as a whole by the numeral 10. The base structure conveniently may be made of tubular metal members adequately cross-braced at the ends and sides thereof as shown, and has adjustable leg members 11, 11 by means of which the height of the structure may be adjusted, for a reason subsequently to be explained. Upon its top, the base 10 carries a pair of horizontal, longitudinally extending, shelf-like supporting members 12, 12 disposed at

2

opposite sides of said base, and a second pair of horizontal supporting members 13, 13 extending transversely of the base at opposite ends thereof, slightly below the plane of the supporting members 12.

Mounted upon the supporting members 12 at one end thereof (the left as viewed in Fig. 1), and spanning the space between said members is a frame member 15. A substantially similar frame member 16 is similarly mounted at the opposite end of the apparatus, said frame members being connected to each other and mutually braced by a smooth cylindrical tie-bar 17 at the tops thereof. The bar 17 is horizontally disposed and lies in the central longitudinal plane of the apparatus. Jounaled adjacent its ends in the respective frame members 15, 16, parallel to the tie-bar 17 and substantially below the latter, is a rock-shaft 18, which rock-shaft has a flat chordal surface 19 extending longitudinally thereof throughout its entire length. The rock-shaft 18 supports the warp-handling arms of the apparatus, which arms are of two different constructions, and are arranged in alternation upon the shaft.

The construction of the warp-handling arms is best shown in Figs. 4, 5, and 6 whereof Fig. 4 shows one type of arm, designated 20, and Figs. 5 and 6 show the other type of arm, designated 21. The arm 20 is a relatively thin metal structure having a disc-like hub portion in which is located an axial aperture 22 that is shaped complementary to the cross-sectional shape of the rock-shaft 18, that is, the said aperture is formed with a chordal flat portion similar to the flat portion 19 of the rock-shaft. The arrangement is such that oscillation of the rock-shaft will oscillate the arms 20 in unison. Extending longitudinally through each arm 20 is a duct or passage 23, which, in the hub portion of the arm is arcuate so as to avoid the aperture 22 therein. One end of the passage 23 is at the free end of the arm, the other end being located on the periphery of the arm-hub diametrically opposite the point where the arm is connected thereto. The passage 23 is designed to receive one of the warp strands to be woven, and its terminal orifices are flared, parallel to the plane of the arm, to avoid the exerting of shearing strain on the warp-strand during the weaving operation.

The arms 21 are substantially similar to the arms 20, each having a passage 25 extending longitudinally therethrough, which passage curves about an axial aperture 26 formed in the hub portion of the arm. The aperture 26 is circular in shape so that the arm is journaled on the rock-shaft 18 on which it is mounted, and may be oscillated relatively of the shaft and relatively of the other warp-handling arms 20. Each arm 21 has a radial extension 27 on the diametrically

opposite side of its hub portion, the passage 25 extending longitudinally through said extension and having its terminal orifice in the end thereof flared parallel to the plane of the arm. The outer end portion of the extension 27 has divergent lateral margins so as to constitute a head portion 28, and the head portions of all the arms 21 are received and securely engaged in a channel-shaped yoke or clip 29, the arrangement being such that the latter may be utilized to effect oscillation of all the arms 21 in unison. The base of the channel-shaped clip 29 is formed throughout its length with a series of parallel oblique slots 30, 30, which slots will register with the ends of the passages 25 in the extensions 27 of the arms 21, and thus enable warp-strands to enter the respective passages 25.

The purpose of the clip 29 is to enable power to be applied concurrently to all the warp-handling arms 21 to oscillate them about their supporting shaft 18. To this end each end portion of said clip is formed with a pair of upstanding apertured ears 32, and pivotally connected to said pairs of ears are respective angular links 33. The links 33 are parallel to each other, and extend toward the rear of the machine where their rear ends are pivotally connected to power-driven means that impart reciprocatory movement thereto. At the left end of the apparatus as viewed in Fig. 1, the rear end of the link 33 is pivotally connected to a rotary disc 34, eccentrically of the axis thereof. At the opposite end of the machine the link 33 is pivotally connected at 35 to the lateral face of a gear 36, eccentrically of the axis of said gear. The disc 34 and the gear 36 are keyed upon an intermittently rotating shaft 37, the latter being journaled adjacent its respective ends in the frame members 15, 16. The links 33 are required to be angular since they extend across and over the rock-shaft 18 in one phase of operation, as shown in Fig. 2. The arrangement is such that rotation of the shaft 37 will impart oscillatory movement of substantially 155 degrees to the warp-handling arms 21. Since power is applied concurrently to both ends of the clip 29, the entire series of arms 21 is maintained accurately in alignment.

As previously stated, the warp-handling arms 20 are oscillated in unison by the rock-shaft 18 on which they are mounted, and such oscillation is concurrent with the oscillation of the arms 21, but in the opposite direction, so that the arms 20, 21 pass each other twice during each complete revolution of the shaft 37. For oscillating the shaft 18, respective lever arms, such as the lever arm 40, Fig. 2, are secured to opposite ends thereof, the free ends of said lever arms being pivotally connected to respective links 41 at one end of the latter. At the left end of the apparatus, as viewed in Fig. 1, the opposite end of link 41 is pivotally connected to a rotary disc 42, eccentrically of the axis thereof. At the opposite end of the apparatus, the link 41 thereat has its opposite end pivotally connected at 43 to a lateral face of a gear 44, eccentrically of the axis thereof. The disc 42 and gear 44 are keyed to opposite ends of an intermittently rotating shaft 45 that is journaled adjacent its respective ends in the frame members 15, 16. The shaft 45 is parallel to the shaft 37 and rock-shaft 18, but is located toward the front of the machine whereas shaft 37 is located at the rear thereof. The shaft 45 is somewhat longer than the shaft 37 and rock-shaft 18, so that the link 41 does not require to be angular as do the links 33.

Gear 44 is of the same size as gear 36, and the distance from the axis thereof to pivotal connection 43 is the same as the distance from the axis of gear 36 to pivotal connection 35, the arrangement being such that rotation of shaft 45 imparts the same angle of oscillatory movement to the arms 20 as the rotating shaft 37 imparts to the arms 21. By employing two lever arms 40 on the shaft 18, power is applied to both ends thereof and torsional strain thereon is avoided.

For driving shaft 45, the gear 44 thereon is meshed with a gear 48 that is fixed on the outer end of a stub shaft 49 that is journaled in a bearing structure 50 formed on the frame member 16. Also fixed on the stub shaft 49, so as to rotate with gear 48 thereon, is a gear 51, and the latter is meshed with a gear 52, Fig. 2, that is journaled on a stub shaft 53 that projects laterally from frame member 16, parallel to stub shaft 49 and in the same horizontal plane as the latter. Gear 52 also is meshed with gear 36 that is mounted on shaft 37, as hereinbefore described. Gears 36, 44, 48, 51 and 52 as shown are all of the same size, the arrangement being such that when motion is imparted to the gear train, shafts 37 and 45 will be rotated at the same angular speed.

Operation of the gear train is effected by rotary motion imparted intermittently to the gear 52. To this end a pulley 55 is journaled on the stub shaft 53 at one side of gear 52, said pulley being operatively connected to said gear by an interposed volute spring 56, one end of which is connected to the pulley and the other end of which is connected to the gear. Trained about the pulley 55 is a side-driving transmission belt 57 that has driving connection with any suitable rotary prime mover (not shown), such as an electric motor. When the pulley 55 is driven in the direction indicated by the arrow in Fig. 2, the spring 56 tightens until it overcomes the resistance of the gear train, and then drives the latter and parts connected therewith.

As previously has been stated, the shafts 37 and 45 are rotated intermittently, and this result is achieved by means periodically and yieldingly obstructing rotation of the gear 52. To this end a pair of studs 60, 60 are mounted upon the gear 52 and project laterally therefrom at diametrically opposite points. Mounted upon the frame member 16, beyond the perimeter of gear 52, is a device that comprises a lever arm 61 that is pivoted at 62, one end of said arm projecting into the orbit of the studs 60. The other end of arm 61 is provided with a roller 63 that rests upon a yielding plate 64 that is backed by a compression spring 65. Said plate and spring are mounted in a cylindrical housing 66, the plate 64 being located at the top of the housing and retained therein by an overhanging flange on the housing. An adjusting screw 67 is threaded through the bottom of the housing and engages a spring-seat 68 disposed beneath the spring 65, the arrangement being such that the force of the spring acting against plate 64 may be adjusted by means of the screw 67. As the gear 52 is driven by the pulley 55 through the agency of the volute spring 56, the studs 60 periodically and in succession engage the end of lever arm 61. Resistance to movement of said lever arm is sufficient to stop rotation of the gear 52, and other gears connected thereto. Such stoppage of the gear 52 is of relatively brief duration, but during said stoppage the pulley 55 continues to rotate and stores up energy in the volute spring 56. The force of the compres-

sion spring 65 is so adjusted, that it is overcome by the stored up energy in the volute spring 56 before the pulley 55 has made half a revolution. When this occurs, the stud 60 engaging lever arm 61 is enabled to tilt the latter, against the force of spring 65, sufficiently to pass said lever arm, whereupon the spring 56 turns the gear 52 forwardly to the position it would have reached had its rotation not been interrupted. The rotation of the gears is stopped twice during each revolution of the pulley 55, whereby intermittent rotary movement is imparted to the shafts 37 and 43.

The warp-handling arms 20, 21 perform the functions ordinarily performed by the heddles of conventional looms, that is, they separate the alternate warp strands periodically to form a "shed," and the weft strand is woven into the warp strands by a shuttle that passes back and forth through the shed. In the drawings the warp strands are shown at 70, 70. They pass through the passages 23, 25 of the warp handling arms 20, 21, the strands entering said passages at the top thereof and being drawn from the passages at the bottom of the arms. The supply of warp strands may consist of the usual creels, cops, or warp beams (not shown) from which said strands are drawn. Said supply is located above and at opposite sides of the apparatus, the strands passing partly around the tie-bar 17 in their passage from the supply to the arms 20, 21. If desired, any suitable or conventional means (not shown) may be employed between the loom and the warp-supply for imparting tension to the warp strands. However, the passages 23, 25 of the warp-handling arms are arcuate in the hub portions of said arms, and the friction produced by passage of the warp strands through said passage may impart adequate tension to the strands, so that no other tension-producing means are required.

The weaving operation is effected below the warp-handling arms 20, 21, where a weft strand 72 is deposited between the respective groups of warp strands 70 as the arms 20, 21 are oscillated. For laying the weft strand, the conventional shuttle 73 is illustrated herein, but the invention contemplates that other weft-laying means, such as needles, may be employed if desired. The shuttle 73 passes through the shed of warp strands, as shown in Figs. 3 and 8, during those intervals when there is a dwell in the oscillatory movement of the arms 20, 21 as the result of the intermittent rotary movement of the shafts 37 and 45. At each end of the loom are the usual shuttle boxes 74 that receive the shuttle after each traverse of the warp shed, said shuttle boxes being mounted upon the supporting members 13 at each end of the loom. The usual picker sticks 75, 75 for impelling the shuttle through the warp-shed are located at opposite ends of the loom. Mechanism for actuating the picker sticks 75 at determinate intervals during operation of the loom is not illustrated herein since it constitutes no part of the present invention, it being understood that any desired or conventional mechanism may be employed for the purpose. At the bottom of the loom is shown a box-like receptacle 76 in which the woven material, indicated at 77, is received.

In the operation of the loom, the warp-strands 70 are drawn from their source of supply and threaded through the warp-handling arms 20, 21 as shown. The shuttle 73 is supplied with a bobbin (not shown) of weft material 72 in the usual manner. At the beginning of operation the warp strands 70 may be attached to a suitable weighted

bar (not shown) below the arms 20, 21, which bar will impart tension and a gravity pull on the warps. The prime mover is then placed in operation to effect oscillation of the arms 20, 21 in the manner hereinbefore described, and to actuate the picker sticks 75 at proper intervals. Oscillation of the arms 20, 21 causes the respective banks of warp strands periodically to cross each other, the weft strand 72 being passed through the shed of warp strands each time the said arms pause in their oscillatory movement, as shown in Figs. 3 and 8. When the arms 20, 21 pass each other they are in vertical position, whereas at the extremities of their oscillatory movement they are substantially 155° apart. Thus the free ends of said arms are at a substantially greater elevation at the extremities of their oscillatory movements than when crossing each other, as will be obvious from a comparison of Figs. 7 and 9. Since the woven material 77 is not anchored at its lower or leading end, the result of the oscillation of arms 20, 21 is to raise and lower the unsupported portion of the woven material, that is, the portion thereof that is not resting upon the bottom of the container 76. The weight of the suspended woven material keeps the warp strands taut and under tension, and such tension may be varied by varying the proximity of the container to the warp-handling arms, the adjustable leg members 11 of the loom-base being provided for this purpose.

When the arms 20, 21 are at the extremities of their oscillating movement, the woven material 77 is in lifted position, and the warp strands 70 are pulled taut in opposite directions to positions 35 where all are disposed almost at right angles to the woven material 77, as is clearly shown in Fig. 7. This is an important feature of the invention since the result thereof is to pack the weft strand 72 tightly in place, thus obviating the use of batten and reed conventionally employed for this purpose.

Although in the loom illustrated the woven material moves in a vertical direction, the invention is not limited to this arrangement, it being contemplated that the novel features of the invention may be used in looms wherein the woven material is horizontally disposed.

The loom may be employed for weaving full-width fabrics, or for weaving relatively narrow fabrics. The latter arrangement is shown in Fig. 1 of the drawings to simplify illustration. For weaving narrow fabrics only a portion of the arms 20, 21 need be utilized, the remainder being unthreaded so as to idle during the weaving operation, or being removed entirely from the loom as shown.

The invention results in simplicity of construction of the loom, conservation of floor space, and the achievement of the other advantages set out in the foregoing statement of objects.

Modifications may be resorted to without departing from the spirit of the invention or the scope thereof as defined by the appended claims.

What is claimed is:

1. A weaving loom comprising warp-shed forming mechanism, and a shuttle adapted to pass through the shed to lay a weft strand therein, said shed-forming mechanism comprising a plurality of individual oscillatable members for the respective warp strands, means for oscillating adjacent members in opposite directions through determinate angles to form a shed, and means for effecting a dwell in the oscillating movement of said members, intermediate the extremities of such movement, when the shed is of a size that

ables the shuttle most readily to pass therethrough.

2. A weaving loom comprising warp-shed forming mechanism, and a shuttle adapted to pass through the shed formed thereby, said shed-forming mechanism comprising a plurality of warp handling arms arranged on a common axis, means for oscillating alternate arms in unison, means for concurrently oscillating the arms intermediate thereto in unison to the same extent and in the opposite direction to the said alternate arms, and means common to the said alternate and intermediate arms for effecting a dwell in the oscillating movement thereof, intermediate the extremities of such movement, when the shed is of a size that enables the shuttle most readily to pass therethrough.

3. A weaving loom of the character described comprising a warp-shed forming mechanism, and a shuttle adapted to pass through the shed formed thereby, said shed-forming mechanism comprising a plurality of warp-handling arms for respective warp strands, a rock-shaft upon which said arms are mounted in side by side relation, alternate arms having driving engagement therewith, and the intermediate arms being journaled thereon, means for rocking the rock-shaft to oscillate the arms having driving engagement therewith, and means for concurrently oscillating the other arms in the opposite direction.

4. A combination as defined in claim 3 wherein the arms that are journaled on the rock-shaft are provided with respective extensions, including a member engaging all of said extensions and connected to the means that effects oscillation of this group of arms.

5. A weaving loom of the character described comprising a warp-shed forming mechanism, and a shuttle adapted to pass through the shed formed thereby, said shed-forming mechanism comprising a plurality of warp-handling arms for respective warp strands, a rock-shaft on which said arms are mounted in side by side relation, alternate arms being fixed to the rock-shaft to turn therewith and the intermediate arms being journaled thereon, a member connecting all the said intermediate arms so that they may operate in unison, a lever arm on the rock-shaft, a link connecting said lever arm to a rotary member constituting a crank, a link connecting the member that connects the intermediate arms to a rotary member constituting a crank, respective shafts on which said rotary members are mounted, and means for intermittently rotating said shafts in unison.

6. A combination as defined in claim 5 wherein the last mentioned means comprises a train of gears connecting the last mentioned shafts to each other, a constantly driven power operated pulley, means between said pulley and one of said gears for storing up energy, and means for intermittently preventing rotation of said gears.

7. A combination as defined in claim 5 wherein the last mentioned means comprises a train of gears connecting the shafts to each other, a constantly driven rotating pulley, a volute spring between said pulley and one of said gears adapted to store up energy when the train of gears is idle, and yielding means periodically impeding rotation of said gears, said yielding means adapted to be overcome by the energy stored in said spring.

8. A weaving loom of the character described comprising a warp-shed forming mechanism and

7 a shuttle adapted to pass through the shed formed thereby, said shed-forming mechanism comprising a plurality of warp-handling arms, means mounting said arms on a common horizontal axis, means oscillating said arms in unison to each side of a central vertical plane with adjacent arms moving in opposite directions, means imparting a dwell during each oscillation of the arms intermediate their extremities of oscillation to enable the shuttle to pass through the shed formed thereby, whereby is woven a web that is suspended from said arms, and means for controlling the weight of the suspended web.

9. A combination as defined in claim 8 wherein the last mentioned means comprises a receptacle 15 mounted below the warp-handling arms adapted to receive the woven web, and means for varying the distance between the said arms and the receptacle to vary the length of the suspended portion of the web.

10. The method of weaving which comprises feeding warp strands to a weaving point, separating groups of alternate warp strands periodically to form a succession of sheds, passing a weft strand through each of the sheds as it is formed, crossing the warp strands over the weft strand to confine the latter, and then pulling said warp strands substantially in opposite directions transversely of the direction of feed to apply force to the weft strand to pack it into place, said force being uniform in its application to successive passes of the weft strand.

11. The method of weaving which comprises feeding warp strands to a weaving point periodically, separating groups of alternate warp strands to form a succession of sheds, passing a weft strand through the respective sheds, crossing the warp strands over the weft strand to confine the latter, pulling said warp strands in opposite directions and to equal extent after each pass of the weft strand, and so moving the woven material and weaving point relatively of the warp strands that the latter are disposed substantially at right angles to the woven material to force the weft strand into place.

12. A method as defined in claim 11 wherein the moving of the woven material and weaving point relatively of the warp strands is yieldingly opposed.

13. A method as defined in claim 11 wherein the moving of the woven material and weaving point relatively of the warp strands is opposed by the static weight of a determinate quantum of previously woven material.

55 SAMUEL KAUFMAN.
